(57) **CLAIM**

The ornamental design for a card holder as shown and described.

DESCRIPTION

FIG. 1 is an isometric view of the first embodiment of a card holder, showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 top plan view thereof.

FIG. 7 is a bottom plan view thereof.

FIG. 8 is a cross section view taken along line 8-8 of FIG. 2.

FIG. 9 is an enlarged detailed view of the top portion of FIG. 8 labeled by arrow.

FIG. 10 is a cross section view taken along line 10-10 of FIG. 2.

FIG. 11 is an enlarged detailed view of the right portion of FIG. 10 labeled by arrow.

FIG. 12 is an exploded perspective view of FIG. 1 shown in an environment of use.

FIG. 13 is an isometric view of the second embodiment of a card holder.

FIG. 14 is a front elevation view thereof.

FIG. 15 is a rear elevation view thereof.

FIG. 16 is a left side elevation view thereof.

FIG. 17 is a right side elevation view thereof.

FIG. 18 top plan view thereof.

FIG. 19 is a bottom plan view thereof.

FIG. 20 is a cross section view taken along line 20-20 of FIG. 14.

FIG. 21 is an enlarged detailed view of the top portion of FIG. 20 labeled by arrow.

FIG. 22 is a cross section view taken along line 22-22 of FIG. 14.

FIG. 23 is an enlarged detailed view of the right portion of FIG. 22 labeled by arrow.

(Continued)

FIG. 24 is a cross section view taken along line 24-24 of FIG. 14.

FIG. 25 is an enlarged detailed view of the right portion of FIG. 24 labeled by arrow; and,

FIG. 26 is an exploded perspective view of FIG. 13 shown in an environment of use.

The even broken lines show portions of the article and form no part of the claimed design. The dot-dash lines in FIGS. 12 and 26 illustrate environment and form no part of the claimed design.

1 Claim, 17 Drawing Sheets
